TREAD BLOCK CORE FOR ENDLESS TRACKS AND THE LIKE

Edwin L. Allen and Harold B. Muster, Cleveland Heights, Ohio, assignors to Rudolph I. Schonitzer, Shaker Heights, Ohio

Application February 5, 1942, Serial No. 429,604

15 Claims.

(Cl. 305—10)

This invention relates to endless tracks for vehicles such as tanks, tractors and the like. More particularly, the present invention relates to improvements in the re-enforcing cores for the rubber tread blocks of such tracks.

The type of tread block core with which the present invention is concerned is one having a pair of metal tubes adjacent, and substantially parallel with, the front and rear ends of the core, for the extension therethrough of cross rods by means of which a set of tread blocks, containing cores of the character here involved, may be connected to form an endless track, the laterally projecting end portions of said cross rods being suitably connected in pairs, at each side of the track, by means not necessary to be here described.

The present invention has for its general object the provision of a tread block core in which the metal tubes thereof are mounted in a simple and inexpensive sheet metal support of great structural strength and rigidity, as a consequence of which said core is particularly well adapted for the effective re-enforcement of the rubber which is bonded to opposite faces of said core to form a tread block.

A further object of the present invention is the provision of a tread block core which comprises a pair of tubular members and a sheet metal support therefor of box-like form in which said tubular members are mounted, said support being provided with re-enforcing parts so constructed and arranged as to materially increase the strength, rigidity and durability of said support and hence, of the core as a whole.

A further object of the present invention is the provision of a tread block core which comprises a pair of metal tubes and a support therefor in the form of a pair of rigidly connected sheet metal members of cup-like character, the end portions of said tubes being rigidly mounted in apertures in the base portions of said cup-like members to thereby provide a unitary core of unusual sturdiness.

Further objects of the present invention will appear from the following description of two tread block cores embodying said invention, said cores being illustrated in the accompanying drawings, in which

Fig. 1 is a top plan view of a section of one form of endless track having rubber tread blocks provided with cores embodying the present invention, the means by which are connected the laterally projecting end portions of the cross rods which extend through said tread blocks to

maintain them in endless track form being omitted, inasmuch as said connecting means is not here involved;

Fig. 2 is a view, partly in vertical section and partly in side elevation, of the track section of Fig. 1, the view being on the line 2—2, Fig. 1;

Fig. 3 is a top plan view of one of the cores of the side tread blocks of the track of Fig. 1, the cores of the other side tread blocks of such track being identical therewith;

Fig. 4 is a side elevational view of the core of Fig. 3, and showing in dot-dash lines the outer periphery of the block of rubber in which said core is embedded to form a side tread block;

Fig. 5 is a cross sectional view of a side tread block containing the core of Fig. 3, the view being on the line 5—5, Fig. 4;

Fig. 6 is a top plan view of one of the two duplicate cup-like members of the core of Fig. 3;

Fig. 7 is a side elevational view of the cup-like core member of Fig. 6;

Fig. 8 is a top plan view of the transversely split core of one of the correspondingly split middle tread blocks of the track of Fig. 1, the cores of the other middle tread blocks of such track being identical therewith;

Fig. 9 is a side elevational view of the two-sectional core of Fig. 8, and showing in dot-dash lines the outer peripheries of the two-sectional block of rubber in which the two sections of said core are embedded to form a transversely split middle tread block;

Fig. 10 is a rear elevational view of the front section of a middle tread block containing the front section of the core of Fig. 8;

Fig. 11 is a top plan view of the one of the two duplicate parts of one of the two duplicate cup-like members of the tread block core of Fig. 8;

Fig. 12 is a side elevational view of the core part of Fig. 11;

Fig. 13 is a top plan view of one of the two duplicate sheet metal re-enforcing members which are used in the core of Fig. 8, there being one such re-enforcing member in each of the front and rear sections of said core; and

Fig. 14 is an end elevational view of the re-enforcing member of Fig. 13.

Before the present invention is described in detail, it is to be understood that such invention is not limited to the details of construction or the specific arrangement of parts herein illustrated or described, as the invention obviously may take other forms. It also is to be understood that the phraseology or terminology herein employed is for the purpose of description and not

of limitation, the scope of the present invention being indicated by the appended claims.

Referring first to Figs. 1 and 2, there is shown in such views a section of an endless track which comprises three rows of generally rectangular, longitudinally disposed rubber tread blocks each containing a core embodying the present invention, there being two laterally spaced rows of side tread blocks 10 and a row of middle tread blocks 11, the middle tread blocks being of transversely split form and being staggered with respect to the side tread blocks. The tread blocks of the three rows are maintained in substantially contiguous relationship and in endless track form by cross rods 12 suitably connected at their ends in pairs by means not here shown or described, inasmuch as said connecting means forms no part of the present invention. For the purposes of this application, it is sufficient to point out that each middle tread block 11 is connected to four side tread blocks 10 (two on each side thereof), and that each side tread block is connected to two middle tread blocks, inasmuch as each side tread block is overlapped by the rear section of one middle tread block and by the front section of the adjacent middle tread block, all as clearly shown in Fig. 1.

Inasmuch as the cores of the side tread blocks 10 of the track of Fig. 1 are of identical construction, a description of the core of one such tread block will suffice for all side block cores. Similarly, as the cores of the middle tread blocks 11 of the track of Fig. 1 are of identical construction, it will be necessary to describe the core of but one of those tread blocks, it being understood, of course, that the side tread block cores and the middle tread block cores differ somewhat, as will hereinafter more fully appear.

From an examination of Figs. 3 to 7 inclusive, it will be evident that the core of each of the side tread blocks 10 comprises a pair of tubular members, such as the metal tubes 15, and a sheet metal support therefor of box-like form, the side walls of said support being suitably apertured to receive the ends of said tubes.

As here shown, the support for the tubes 15 comprises a pair of sheet metal members 16 of cup-like form, said members being arranged side-by-side with their rim portions in contact and with their base portions 17 constituting the side walls of the support. For manufacturing economy and simplicity of assembly, the two tubes 15 preferably are of duplicate character, as here shown. Similarly, the two cup-like members 16 preferably, and here are, of duplicate form, although it is to be understood that the cores of the side tread blocks 10 may be of the type in which the two tubes thereof are not duplicates and in which the sheet metal members forming the support for said tubes are not identical.

In order to provide a more rigid and sturdier core, the cup-like members 16 preferably, and here are, of such size as to snugly receive the tubes 15, and inasmuch as said tubes are located at the front and rear ends of said members, the curvature of the end portions of said members is such as to conform to the curvature of said tubes, as best shown in Fig. 4. For the formation of the circular apertures 18 which receive the ends of the tubes 15, the entire end areas of the base portions 17 of the cup-like members 16 are removed, and in order to provide increased bearing surface for the inner or contiguous semi-circular sections of the ends of said tubes, the end edge portions of the remaining metal of the base por-

tions 17 of members 16 are laterally bent to form the semi-circular flange portions 19. These flange portions 19 are here readily formed by inwardly offsetting the metal therebetween, which results, of course, in giving the cup-like members 16 increased strength and rigidity, as will be readily understood.

Any suitable means may be utilized for maintaining the cup-like members 16 in associated relationship and for preventing endwise movement of the tubes 15 relative to said members. As here shown, the members 16 are maintained in abutting relationship by flash welding, and copper brazing is utilized to rigidly connect the ends of the tubes 15 to the side edges of the rounded end portions of members 16 and to the arcuate flanges 19 of the base portions 17 of said members. It is not essential, of course to separately unite, by welding or other means, the two cup-like members 16 as they will be held in abutting relation by the means, whatever be its form or character, by which the ends of the tubes 15 are rigidly united to said members, all as will be readily understood.

From the foregoing description of the core of the side tread blocks 10, it will be evident that said core is particularly well adapted for the effective and durable re-enforcement of the block of rubber 20 in which said core is embedded to form a side tread block. Any suitable means may be utilized, of course, for the bonding of said rubber to said core, the outer surfaces of the sheet metal members 16 being copper plated for such purpose, if desired. The inward offsetting of the base portions 17 of members 16 naturally is of material benefit in the securement of said rubber to the core, as it enables the rubber to extend along the sides of the core between the arcuate flanges 19, as clearly shown in Fig. 5. If desired, the diameter of the tubes 15 may be such as to more or less snugly receive the cross rods 12 or, as here shown (see Fig. 2), the diameter of said tubes may be somewhat larger than that of said cross rods in order that said tubes may be provided with rubber or other linings 21.

Referring now to Figs. 8 to 14 inclusive, wherein is illustrated the core of the middle tread blocks 11, it will be noted that said core also comprises a pair of metal tubes and a sheet metal support therefor of box-like form, the side walls of said support being apertured to receive the ends of said tubes. It also will be noted that said support comprises a pair of sheet metal members 16a of cup-like form and preferably of duplicate character, said members being arranged side-by-side with their rim portions in contact and with their base portions 17a constituting the side walls of the support.

In this core, however the tubes 15a do not snugly fit within the cup-like members 16a nor do said tubes engage the rounded front and rear end portions of said members. As clearly shown in Fig. 8, the circular apertures 18a in the base portions 17a of members 16, for the reception of the ends of the tubes 15a, are spaced from the rounded end portions of said members, and are surrounded by out-turned annular flanges 24 with which the base portions 17a are here integrally provided.

To simplify replacement in the field of tread blocks of the character here involved, the middle tread blocks 11 are of transversely split form, with the result that each such tread block includes a front section and a rear section, the two sections preferably being of duplicate character,

as here shown. The cores of the middle tread blocks are, of course, of correspondingly split form, so that each of the cup-like members 16a is in two duplicate parts.

Any suitable means may be utilized for maintaining in associated relationship the rear parts of members 16a and for preventing endwise movement relative thereto of the rear tube 15a which is mounted therein. Similarly, any suitable means may be utilized for maintaining in associated relationship the front parts of members 16a and for preventing endwise movement relative thereto of the front tube 15a which is mounted therein. As here shown, flash welding is used to maintain in abutting relationship the rear parts of members 16a, and the front parts of such members are likewise maintained in abutting relationship by flash welding. For the rigid connection of each tube 15a to the annular flanges 24 of the sheet metal core parts in which it is mounted, copper brazing is here used. It is not necessary, however, to separately unite, by welding or other means, either set of associated core parts, as the two sheet metal parts of each such set will be securely held in abutting relationship by the means, whatever be its form, by which is rigidly connected thereto one of the tubes 15a.

In order to give this middle tread block core increased strength and rigidity, each section of said core is here provided at its abutment end 25 with a suitable re-enforcing member, such as the channel-shaped sheet metal member 26 here shown (said member being illustrated per se in Figs. 13 and 14). As best shown in Figs. 8 and 9, these re-enforcing members are arranged within and transversely of the cup-like members 16a, the top and bottom flanges 27 of said re-enforcing members being in contact with and rigidly secured to the top and bottom wall portions of members 16a by copper brazing, welding or other suitable means. As best shown in Figs. 8 and 10, the length of the re-enforcing members 26 is such that they abut or substantially abut the base portions 17a of members 16a, although they obviously may be of somewhat shorter length, if desired. Moreover, if desired and as here shown, the re-enforcing members 26 may have their middle portions recessed, as at 28, the effect of which is to give them increased strength and rigidity, as will be readily understood.

From the foregoing description of this middle tread block core, it will be evident that such core is particularly well adapted for the effective and durable re-enforcement of the two-sectional block of rubber 30 in which such core is embedded for the formation of a middle tread block, each section of said rubber block being suitably bonded to the core section embedded therein, as will be readily understood. It also will be evident that the provision of the annular flanges 24 of the base portions 17a of the cup-like members 16a not only afford increased bearing surface for the ends of the tubes 15a but also aid in the anchoring to each core section of the section of rubber in which it is embedded.

Inasmuch as the cross rods 12 fit tightly in the tubes 15 of the cores of the side tread blocks 10 (said tubes being frequently rubber lined, as here shown), it is quite advantageous to make the middle tread blocks 11 of transversely split form. This enables factory assembled replacement units to be used in the field if replacement of a side tread block or a middle tread block section becomes necessary or desirable. Each such replacement unit consists of a pair of cross rods 12 on

5 which are mounted two side tread blocks and two middle tread block sections therebetween, said sections constituting, when in a track, the adjacent sections of two adjacent middle tread blocks, all as will be readily understood. As will be evident from the accompanying drawings, the two sections of each middle tread block 11 are firmly held in abutting relation by the means (not shown) by which the cross rods 12 are connected in pairs, and any tendency of a middle tread block section to turn about its cross rod is effectively resisted.

Further features and advantages of tread block cores embodying the present invention will be evident to those skilled in the art to which the present invention relates.

What we claim is:

1. A core for the rubber tread block of an endless track of the type in which the tread blocks of such track have cross rods extending therethrough, said core comprising a pair of spaced tubular members for the reception of track cross rods, and a sheet metal support for said tubular members and having a member of elongated cup-like form.

2. A core for the rubber tread block of an endless track of the type in which the tread blocks of such track have cross rods extending therethrough, said core comprising a pair of spaced tubular members for the reception of track cross rods, and a sheet metal support for said tubular members in the form of a pair of elongated cup-like members.

3. A core for the rubber tread block of an endless track of the type in which the tread blocks of such track have cross rods extending therethrough, said core comprising a pair of spaced tubular members for the reception of track cross rods, and a sheet metal support for said tubular members, said support comprising a pair of elongated cup-like members arranged with their rim portions in adjacent relationship.

4. A core for the rubber tread block of an endless track of the type in which the tread blocks of such track have cross rods extending therethrough, said core comprising a pair of spaced tubular members for the reception of track cross rods, and a sheet metal support for said tubular members, said support comprising a pair of elongated cup-like members arranged with their rim portions in abutting relationship.

5. A core for the rubber tread block of an endless track of the type in which the tread blocks of such track have cross rods extending therethrough, said core comprising a pair of spaced tubular members for the reception of track cross rods, and a sheet metal support for said tubular members, said support being of box-like form with apertured side wall portions, said wall portions being provided with laterally extending annular flanges surrounding said apertures, and said tubular members being mounted in the apertures of said wall portions and bearing against the flanges thereof.

6. A core for the rubber tread block of an endless track of the type in which the tread blocks of such track have cross rods extending therethrough, said core comprising a pair of spaced tubular members for the reception of track cross rods, and a sheet metal support for said tubular members, said support being of box-like form with apertured side wall portions, said wall portions being provided with laterally extending annular flanges surrounding said apertures, and said tu-

bular members being mounted in the apertures of said wall portions and being rigidly secured to the flanges thereof.

7. A core for the rubber tread block of an endless track of the type in which the tread blocks of such track have cross rods extending therethrough, said core comprising a pair of spaced tubular members for the reception of track cross rods, and a sheet metal support for said tubular members, said support being of box-like form with side wall portions, each of said side wall portions having a pair of apertures and an offset strengthening part between its apertures, said tubular members being mounted in the apertures of said side wall portions.

8. A core for the rubber tread block of an endless track of the type in which the tread blocks of such track have cross rods extending therethrough, said core comprising a pair of tubular members for the reception of track cross rods, and a support for said tubular members, said support being of box-like form with apertured side wall portions having outwardly extending annular flanges surrounding their apertures, and said tubular members being mounted in the apertures of said side wall portions.

9. A core for the rubber tread block of an endless track of the type in which the tread blocks of such track have cross rods extending therethrough, said core comprising a pair of spaced tubular members for the reception of track cross rods, and a support for said tubular member, said support being in the form of two associated sheet metal members to which said tubular members are rigidly secured, the securing of said tubular members to the sheet metal members of said support maintaining said sheet metal members in associated relation.

10. A core for the rubber tread block of an endless track of the type in which the tread blocks of such track have cross rods extending therethrough, said core comprising a pair of spaced tubular members for the reception of track cross rods, and a support for said tubular members, said support being in the form of two elongated cup-like members arranged side-by-side, the base portions of said cup-like members constituting the side walls of said support and being apertured to receive the end portions of said tubular members, and means for maintaining said cup-like members in side-by-side relationship.

11. A core for the rubber tread block of an endless track of the type in which the tread blocks of such track have cross rods extending therethrough, said core comprising a pair of spaced tubular members for the reception of track cross rods, and a support for said tubular members, said support being in the form of two elongated cup-like members arranged side-by-side, the base

portions of said cup-like members constituting the side walls of said support, and means for preventing endwise movement of said tubular members relative to said cup-like members.

12. A core for the rubber tread block of an endless track of the type in which the tread blocks of such track have cross rods extending therethrough, said core comprising a pair of spaced tubular members for the reception of track cross rods, and a support for said tubular members, said support being in the form of two associated sheet metal members arranged in side-by-side relationship and in which the end portions of said tubular members are mounted, and means for preventing endwise movement of said tubular members relative to said sheet metal members.

13. A core for the rubber tread block of an endless track of the type in which the tread blocks of such track have cross rods extending therethrough, said core comprising a pair of tubular members for the reception of track cross rods, and a sheet metal support for said tubular members, said support being of box-like form in which said tubular members are mounted, and sheet metal re-enforcing means for said support disposed between said tubular members.

14. A core for the rubber tread block of an endless track of the type in which the tread blocks of such track have cross rods extending therethrough, said core comprising a pair of spaced tubular members for the reception of track cross rods, and a sheet metal support for said tubular members, said support being of box-like form in which said tubular members are mounted, said box-like support being separable into two sections with each such section having a tubular member mounted therein, and a separate sheet metal re-enforcing member for each such section of said support.

15. A core for the rubber tread block of an endless track of the type in which the tread blocks of such track have cross rods extending therethrough, said core comprising a pair of spaced tubular members for the reception of track cross rods, and a sheet metal support for said tubular members, said support being of box-like form with rounded front and rear ends and with apertured side wall portions, the end portions of said tubular members being mounted in said side wall portions adjacent the rounded ends of said support, said support being separable into two sections with such sections having inter-abutting ends and each such section having mounted therein one of said tubular members, and a channel-shaped re-enforcing member for each such section of said support and located adjacent its abutting end.

EDWIN L. ALLEN.
HAROLD B. MUSTER.
